UNITED STATES PATENT OFFICE.

JOHN F. WILLIAMS, OF KANSAS CITY, MISSOURI, ASSIGNOR TO THE ECONOMY GAS LAMP COMPANY, OF SAME PLACE.

DESIGN FOR A LAMP-FIXTURE.

SPECIFICATION forming part of Design No. 30,768, dated May 16, 1899.

Application filed April 26, 1899. Serial No. 714,460. Term of patent 14 years.

To all whom it may concern:

Be it known that I, JOHN F. WILLIAMS, a citizen of the United States, residing at Kansas City, in the county of Jackson and State of Missouri, have invented and produced a new and original Design for Lamp-Fixtures, of which the following is a specification.

My present invention relates to a new and original design for lamp-fixtures, of which the following is a specification, reference being had to the annexed drawing, wherein the fixture is shown in elevation.

The fixture consists of two curved arms A and B, connected at their upper ends to a fitting or casting C, from which extends a straight section D. A reservoir E is mounted upon said section D, and a hook F extends up from the reservoir, as shown.

To the lower end of arm or member B there is secured a fitting or casting G, and extending out horizontally therefrom is an arm H,

which is in line with and stops just short of a horizontally-projecting member I. Said member I is carried by a fitting or casting J, secured to the lower end of arm or member A. 25

Extending down from the fitting J is an arm K, its lower end being bent or curved, forming a horizontal portion L. To the end of said horizontal portion there is secured a casting or fitting M, which forms the burner- 30 support.

Having thus described my invention, what I claim is—

The design for a lamp-fixture herein shown and described. 35

In witness whereof I hereunto set my hand in the presence of two witnesses.

JOHN F. WILLIAMS.
